UNITED STATES PATENT OFFICE.

DAVID A. LEE, OF ALBERTA, LOUISIANA.

SPRING-OPERATED FAN.

Application filed June 21, 1926. Serial No. 117,506.

This invention relates to certain new and useful improvements in fans, and has more particular reference to a fan having spring motor operating means.

5 The primary object of the invention is to provide a spring operated fan which is extremely simple and durable in construction as well as efficient in operation.

10 A further object is to provide a fan including a casing having a spring motor mounted therein for swinging back and forth, and means operatively connecting a driven shaft of the motor with the casing of the fan whereby the motor is bodily oscillated or swung back and forth when the fan is in operation, for obtaining the advantages of an oscillating fan.

15 A still further object is to provide a fan including a spring motor having a driven shaft upon which fan blades are fixed, a casing within which the motor is mounted for oscillation in a lateral direction, and means to automatically cause such movement of the motor upon operation of the fan whereby the 20 latter is caused to oscillate in an arcuate path.

25 Other objects will appear as the nature of the invention is better understood, and the same consists in the novel form, combination and arrangement of parts hereinafter 30 more fully described, shown in the accompanying drawings and claimed.

35 In the drawings, wherein like reference characters indicate corresponding parts throughout the several views,

40 Figure 1 is a view partly in front elevation and partly broken away and in section of a spring operated fan constructed in accordance with the present invention;

45 Figure 2 is a vertical sectional view thereof;

50 Figure 3 is a fragmentary horizontal section taken substantially upon line 3-3 of Figure 2.

55 Figure 4 is a fragmentary vertical section taken substantially upon line 4-4 of Figure 2; and

60 Figure 5 is a fragmentary vertical detail section taken through one of the motor frame plates and associated parts.

65 Referring more in detail to the drawings, the form of the invention illustrated embodies an elongated upright motor frame composed of vertical front and rear frame plates 5 and 6, respectively, rigidly connected in spaced parallel relation by means of a plu-

rality of horizontal connecting rods 7 having spacing sleeves 8 disposed thereon. The rods 7 extend between the plates 5 and 6 and have their ends projecting through horizontally aligned apertures in the plates 5 and 6, the outer ends of the rods 7 being headed as at 9 against the outer surfaces of the plates 5 and 6 for preventing separation of the latter. The spacing sleeves 8 are placed upon the rods 7 so as to extend between the frame plates 5 and 6 and contact the latter at their ends whereby said frame plates are maintained against movement toward each other and in engagement with the heads 9 of the rods 7.

60 The spring motor further includes a horizontal power or winding shaft 11 extending between and having its ends journaled in horizontally aligned openings in the lower 75 portions of the frame plates 5 and 6, and this shaft 11 has a projecting rear end portion 12 of polygonal form for engagement by a winding key as will presently become apparent. A coiled spring 13 is disposed 80 about the forward portion of the shaft 11 between the frame plates and has its inner end attached to said shaft 11 in any suitable manner, the outer end of the spring 13 being suitably anchored to the lowermost sleeve 85 8. Freely rotatable upon the shaft 11 behind the spring 13 is a relatively large gear 15 having a spring pressed pawl 16 pivoted to one side thereof, and fixed on the shaft 11 at the rear side of the gear 15 is a ratchet 90 wheel 17, the teeth of which are normally engaged by said pawl 16 as shown clearly in Figure 4. It will thus be seen that when a suitable winding key 18 is engaged with the polygonal portion 12 of the shaft 11 and 95 the gear 15 held from rotation, the shaft 11 may be rotated for winding the spring 13 and placing the same under tension. The shaft 11, as shown, is to be turned in a clockwise direction when viewing the device as 100 seen in Figure 1 for placing the spring 13 under tension, and upon releasing the gear 15, it will be seen that the spring 13 will unwind thus rotating the shaft 11 in a counterclockwise direction as viewed from the front, 105 thereby turning the ratchet wheel 17 in the same direction. By reason of the fact that the pawl 16 engages the ratchet wheel 17, the gear 15 will be driven in a counterclockwise direction for operating the fan proper 19, in 110 a manner which will presently become apparent.

The fan 19 is of the usual type embodying a plurality of radial twisted blades carried by a hub, and the hub of this fan is fixed upon the forwardly projecting end portion 5 of a horizontal shaft 20 which extends between and is journaled in the frame plates 5 and 6 some distance above the shaft 11. The fan shaft 20 is operatively connected to the motor shaft 11 through a suitable 10 train of gearing whereby the fan 19, as viewed in front elevation, will be driven in a clockwise direction. This train of gearing consists of a pair of counter-shafts 22 journaled in the frame plates 5 and 6 in 15 horizontal spaced relation between the shafts 11 and 20, the lower one of the shafts 22 being provided with a pinion 23 meshing with the gear 15, and a relatively larger gear 24 meshing with another pinion 21 carried 20 by the upper one of the shafts 22. The upper shaft 22 in turn carries a large gear 24^a meshing with a pinion 25 fixed upon the fan shaft 20.

Obviously, any suitable form of manually 25 releasable stop may be provided for restraining the gear 15 from rotation during the winding operation or when the fan is not required for use, such stop means being engaged in any desired one of the rotatable 30 parts in the operative connection between the power shaft 11 and the fan shaft 20.

The spring motor is arranged within a relatively wide box-like casing 26 having an opening in the rear wall thereof as shown 35 in Figure 2 for permitting insertion of the key 18 for engagement with the squared end portion 12 of the shaft 11, and the shaft 20 projects forwardly through a slot 27 in the front wall of the casing 26 so that the fan element 19 is disposed exteriorly of and in front of the casing as shown. The lower end of the motor frame is pivoted upon a horizontal axis so that the motor is capable of oscillating laterally relative to the casing. 40 The pivotal mounting of the motor in this manner may be accomplished in any desired way, and as shown, the lowermost sleeve 8 of the motor frame is rotatably disposed in a bearing provided in the upper end of a post 28 arranged within the bottom of the casing 26 and rigid with and projecting upwardly from the bottom wall of said casing. The lateral oscillation of the motor is permitted by reason of the fact that the slot 27 45 is of arcuate form and concentric with the pivot of the motor frame in the bearing of post 28. In order to automatically effect the lateral oscillation of the motor and the fan element, I provide an operating connection 50 between one of the shafts 22 of the motor and the casing 26. As shown, this operating connection consists in the provision of a crank 29 upon the rear end of the lower counter-shaft 22, and a link 30 having one 55 end pivotally connected to the outer end of

the crank 29 and its other end pivotally attached to the rear wall of the casing 26 as indicated at 31, the point of connection 31 being to one side of the lower shaft 22 as clearly shown in Figure 1.

In operation, the motor is suitably released after winding of the spring 13 so as to cause rotation of the lower counter-shaft 22, and as the outer end of the crank 29 travels in a circular path the motor will be 75 bodily tilted in one direction when the crank 29 pushes against the link 30, while the motor will be swung in the opposite direction when the crank 29 has a pulling action upon the link 30. This results in oscillation of 80 the motor and lateral oscillation of the fan element 19 by reason of the fact that the casing 26 and the connection 31 are fixed or stationary. In this way the fan element 19 will be caused to supply a draught of air 85 over a considerable area as is well known generally with respect to fans of the oscillating type.

From the foregoing description it is believed that the construction and operation 90 as well as the advantages of the present invention will be readily understood and appreciated by those skilled in the art.

Minor changes may be made without departing from the spirit and scope of the invention as claimed.

What I claim as new is:—

1. A fan of the character described comprising a casing, a motor mounted in the casing for lateral oscillation relative to the latter, said motor having a driven shaft projecting through a slot in the front of the casing for permitting the motor to so oscillate, a fan element fixed upon the projecting end of said driven shaft, and means operatively connecting a movable element of the motor with the casing for automatically causing oscillation of the motor upon operation of the latter for rotating said fan element.

2. A fan of the character described including a spring motor, a casing within which said motor is arranged, said motor being mounted at its lower end in the casing for lateral oscillation and having a rotatable driven shaft, and means operatively connecting said driven shaft with the casing for causing lateral oscillation of the motor upon operation of said shaft.

3. A fan of the character described including a spring motor, a casing within which said motor is arranged, said motor being pivoted at its lower end in the bottom of the casing for lateral oscillation and having a rotatable driven shaft, and means operatively connecting said driven shaft with the casing for causing lateral oscillation of the motor upon operation of said shaft, a fan operatively connected to the motor for rotation by the latter and positioned exteriorly 120 of the casing, the operating connection be- 125 130

tween the driven shaft of the motor and the casing comprising a crank on the driven shaft and a link pivoted to the crank and extending to one side of the driven shaft and pivoted to the casing.

4. A fan of the class described comprising a spring motor, a support, means supporting the motor upon the support for lateral oscil-

lation, the motor including a driven shaft, a fan operated by the motor, and means operatively connecting the driven shaft with the support for effecting lateral oscillation of the motor. 10

In testimony whereof I affix my signature.

DAVID A. LEE.
